MICHAEL W. QUIRK, OF MILWAUKEE, WISCONSIN.

BOTTLE OR OTHER RECEPTACLE RECEIVING CRATE.

1,368,290.

Specification of Letters Patent. Patented Feb. 15, 1921.

Application filed September 29, 1919. Serial No. 327,163.

To all whom it may concern:

Be it known that I, MICHAEL W. QUIRK, a citizen of the United States, and resident of Milwaukee, in the county of Milwaukee and State of Wisconsin, have invented new and useful Improvements in Bottle or other Receptacle Receiving Crates, of which the following is a description, reference being had to the accompanying drawings, which are a part of this specification.

The present invention relates to certain new and useful improvements in bottle or other receptacle receiving crates in the form of an open box having means therein for holding the bottles or other receptacles in spaced relation.

In the crates of this class now in everyday use, considerable difficulty has been experienced in that, after continuous usage, the bottom rods, which support the bottles or other receptacles in their respective compartments, become torn from the end members of the crate in which their ends are secured, due to the strain to which they are subjected. The crates that I have reference to are those employing wooden end members, and as will be obvious, the openings in which the ends of the rods are secured become enlarged and elongated after the strain, and in the course of a short time the openings will become so worn that the entire crate will have to be completely rebuilt, by putting in new end members which is considerably costly.

Hence, with the above and other inherent objections in mind which are apparent in the old structure now in use, my invention has for its primary object to provide a bottle or other receptacle receiving container, so constructed that the bottom receptacle supporting rods will not become disengaged from the end members to which they are secured after continuous usage, and which, at the same time, should they become disengaged after prolonged use, may be reinserted without the necessity of supplying entirely new end members.

A more specific object of the present invention is to provide bottom reinforcing strips for the end members of the crate which form shoulders upon which a securing strip connecting the adjacent ends of the bottom rod members rests to provide means for reinforcing the means employed for securing the bottom rods in the crate.

Another object of the present invention is to provide metallic securing strips for connecting the adjacent ends of the bottom receptacle supporting rods and means for securing said strips to the end members of the crate.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing I have illustrated one complete example of the physical embodiment of my invention constructed according to the best mode I have so far devised for the practical application of the principles thereof, and in which:

Figure 1 is a perspective view of a completed bottle or other receptacle receiving crate embodying the various features of my invention.

Fig. 2 is a top plan view thereof.

Fig. 3 is a transverse sectional view therethrough taken on the line 3—3 of Fig. 2.

Fig. 4 is a longitudinal sectional view taken through my crate on the line 4—4 of Fig. 2.

Fig. 5 is an enlarged detail sectional view taken through one portion of the lower part of one of the end members on the line 5—5 of Fig. 6, and

Fig. 6 is an enlarged detail sectional view taken on the line 6—6 of Fig. 5.

Referring now more particularly to the accompanying drawing in which like reference characters designate like parts throughout the several views, the numeral 10 indicates a wooden rectangular crate, having side members 11 and end members 12 which are nailed or otherwise fastened together to form a box-like structure open at its top and bottom. The crate is divided into a plurality of bottle or other receptacle receiving compartments by means of series of spaced longitudinal rods 13 and series of spaced transverse rods 14, which rods have their ends secured in the end and side members respectively, in any desired manner. The lower ends of the receptacle receiving compartments have pairs of bottom sup-

porting rods 15 extending thereacross and secured to the end members in the novel manner now about to be described.

As best shown in Figs. 1, 4 and 5, the 5 lower edges of the end members 12 terminate a short distance above the lower edges of the side members 11 and each has secured thereto by any desired fastening means a reinforcing strip 16 which is slightly thicker 10 than the end members whereby to provide supporting shoulders 17 projecting inwardly of the inner face of the end members adjacent the lower edge of the crate. The adjacent ends of the bottom or supporting rods 15 15 pass through metal securing strips 18 and are then burred over or riveted, as at 19, to secure said rods to said securing strips.

As best shown in Figs. 4, 5 and 6, the securing strips 18 are secured to their adjacent 20 end member 12 by means of rivets or other fastening means 20, the lower edge of each securing strip being recessed upon the adjacent shoulder 17 which is of substantially the same thickness as the securing strip. 25 The bottom rods 15 are medially braced by means of transverse rods 21 extending across the crate near the bottom and having their ends secured in the side members 11.

From the foregoing description taken in 30 connection with the accompanying drawing, it will be readily apparent that the strain applied to the bottom supporting rods 15 is relieved by means of the reinforcing strips 16 and thus practically no strain whatsoever 35 is applied to the rivets 20, and all possibility of the rivets 20 enlarging the openings through which they pass is practically eliminated. At the same time should the strips 16 be dislodged from the end members 12 40 through continuous usage of the crate, and the rivets 20 pulled out of their opening, it will not be necessary to completely rebuild the crate, supplying entirely new end members 12, but it will be necessary to merely 45 drill new holes for the rivets 20 and to supply new reinforcing strips 16. In the old structures the bottom supporting rods 15 are secured in the end members 12 in the same manner as are the rods 13 and 14, and when 50 the rods are torn from the end members, it is impossible to secure them in the same end members by drilling new holes, as the rods 15 must at all times be disposed directly 55 across the bottom of the receptacle receiving compartments. Consequently, my device eliminates these objectionable features.

As will be obvious, the rods 15 with their securing strips 18 provide an insert which may be sold separate from the crate 10 for 60 repairing crates now in use. The insert is

secured in old crates by removing the old bottom rods and then securing the strips 18 to the end members, thus making a used crate practically as strong as a new one at a comparatively low cost. The insert may be 65 sold as an entirety and will provide a strong bottom for crates whether or not it is employed in connection with the reinforcing strips 16.

What I claim as my invention is:

1. A crate of the class described comprising a box-like structure open at its top and bottom, a plurality of receptacle receiving compartments in said crate, bottom rods extending across the bottoms of said compartments to provide rests for receptacles disposed therein, metal securing strips connecting the adjacent ends of said bottom rods, fastening means for securing the metal strips to opposed sides of the crate, and a reinforcing shoulder in said crate adjacent each metal strip and upon which said strips rest, whereby to relieve the strain on the fastening means when receptacles are disposed in the compartments and rest on said bottom rods. 70 75 80 85

2. A crate of the class described comprising side and end members connected together to form a box-like structure open at its top and bottom, said end members terminating a short distance above the lower edges of the side members and each having a reinforcing strip secured to its bottom edge, a plurality of receptacle receiving compartments in said crate, bottom rods extending across the bottoms of said compartments, securing strips connecting the adjacent ends of the bottom rods, and means fixing said securing strips to the end members adjacent said reinforcing strips. 90 95 100

3. A crate of the class described comprising side and end members connected together to form a box-like structure open at its top and bottom, said end members terminating a short distance above the lower edges of the side members and each having a reinforcing strip secured to its bottom edge, said strips being of greater thickness than the end members forming a shoulder on the inner side of each end member adjacent its lower edge, a plurality of receptacle receiving compartments in said crate, bottom rods extending across the bottoms of said compartments, metal securing strips connecting the adjacent ends of the bottom rods and resting on the shoulders of said end members, and means securing said securing strips to the end members. 105 110 115

In testimony whereof I affix my signature.
MICHAEL W. QUIRK.
